FOLDING CHAIR STRUCTURE

Joseph A. Erpelding and Lawrence P. Erpelding,
Indianapolis, Ind.

Application January 15, 1936, Serial No. 59,196

4 Claims. (Cl. 155—141)

This invention relates to a folding chair construction and more especially, it is directed to the combination brace and latch arrangement.

The chief object of the invention is to provide a simplified brace and latch construction for a folding chair of the collapsible parallelogram type.

The chief feature of the invention consists in cooperative relationship between a brace confining plate or guide, a cooperating spring structure and release, and the brace associated therewith.

The full nature of the invention will be understood from the accompanying drawing and the following description and claims:

In the drawing, Fig. 1 is a vertical central section view through a folding chair of a parallelogram, collapsible type, with the parts in chair forming position.

Fig. 2 is a front view of the chair with the parts in collapsed position.

Fig. 3 is a view similar to Fig. 1 and with the parts in the collapsed position.

Fig. 4 is an enlarged central sectional view through the combination brace lock, release and guide showing the brace in chair locking position.

Fig. 5 is a view similar to Fig. 4, showing the brace and the release member in the initial releasing position, preliminary to collapsing or folding of the chair.

Fig. 6 is a view similar to Fig. 5 and with the parts in a subsequent position immediately prior to the complete collapse of the chair.

In the drawing 10 indicates two back legs connected by a rear rail 11, and the rear legs 10 are extended upwardly as at 12. A suitable back structure, herein shown in the form of slats and the like 13, is provided. Another rear rail 14 is pivotally connected as at 15 to the rear legs 10 and straddles the same.

A pair of front legs 16 is connected by a front rail 17 and another rail 18 is pivotally associated as at 19 with said front legs. A plurality of connecting rails 20 is suitably connected at opposite ends to the rails 14 and 18.

An L-shaped bracket 21 is suitably secured as at 22 to the forward corner edges and upon the underside of the seat board 23. The flange 24 of the plate 21 supports a pivot 25 that extends through the front leg 16 at the upper corner thereof.

Seat 23 at its rearward corners has secured to it an L-shaped bracket 26 which is pivotally associated as at 27 with a channel shaped mem-

ber 28 riveted to the rear chair leg as at 29, the two being connected together by the pivot member 27.

The foregoing construction, it will be realized by comparing Figs. 1 and 2, is a parallelogram type, collapsible folding chair. Suitably secured to the seat 23 as at 31 is the padded or upholstered covering 32 for the seat. The upper rearward edge of the front leg is rounded as at 33 to permit folding. Between the two pivots 15 and 21, upon the back leg, there is positioned a channel shaped supporting member 34, secured to said leg by the rivet 35. The intermediate portion upon the inner side of the leg supports a pivot 36 by which is pivotally supported one and a flattened end 37 of an arm that extends from said leg upwardly and inwardly toward the central forward portion of the seat, said extended portion being designated by the numeral 38. Another oppositely directed portion 38 is similarly supported but oppositely directed with reference to the other portion 38 and the two elongated portions are connected together at their upper ends by an intermediate portion 39. The aforesaid constitutes a pivotal V-type brace, as it were.

Secured to the underface of the seat and medially and forwardly thereof, is a strap type socket having the two substantially aligned spaced portions 40 and 41 apertured as at 42 for the reception of anchoring screws 43, or the like, whereby the strap is secured to the seat. The strap includes a slight offset portion 44 which is apertured as at 45 to receive one end 46 of a spring member having a portion 47 positioned at right angles to portion 46 and extending forwardly through the space between the underface of the seat 23 and the additional offset portion 48 of the strap. Portion 47 is a resilient wire which has an inclined portion 49 that extends forwardly and is provided with a half loop 50 which in turn is provided with a half loop 51, the free end thereof terminating in a portion 52 normally lying parallel to portion 47 and provided with a circular formation 53 for facilitating finger grip-

portion 48 of the strap terminates in a downwardly directed portion 54 united by a curved portion 55 to a parallel and upwardly directed portion 56, in turn connected with portion 40. This forms a groove or trough for the seating of the intermediate portion 39 of the V-shaped brace. Portion 54—55—56 and a considerable portion of the portion 48 of the socket or strap construction, are medially slotted as at 57 to per-

mit the wire portions 50—51 and 52 as well as a slight portion of portion 49, to pass through the end of the strap. The resulting structure is a combination brace lock and release of extremely simple form and of positive character. As shown in Fig. 4, the parts are held in locked position by the spring portion 49.

In order to fold the chair, the portion 53 is engaged and drawn toward the seat which elevates the portion of the spring associated therewith and removes the portion 49 from the slot 57 in portion 48 and serves to elevate the intermediate portion 39 out of the groove formed by the portions 54, 55 and 56 of the strap. Then as soon as the portion 39 has cleared the groove in the strap, upward movement of the front of the chair seat occasioned by slight upward pressure on the portion 53 will cause the seat to be folded upwardly and rearwardly, the front legs in turn folding downwardly and rearwardly relative to the back. In this folding movement, the portion 39 moves toward the rear portion 42 and near the end of the movement is entirely freed from engagement with the spring portion 49 so that the spring member 47—49 normally reseats in the strap slot.

Upon the unfolding or extending movement, the reverse arrangement is obtained. As the seat swings forwardly and downwardly, portion 39 engages the inclined portion 49 and forces the spring to withdraw from the slot 57 in the portion 48 and causes said portion 49 to lie substantially as shown in Fig. 6, until the portion 39 has passed beyond the extreme forward edge of portion 48 of the strap and is then free from bearing thereon. When that occurs, spring 49 immediately becomes operative and tends to force member 39 into the groove of the strap. When that occurs, the member 39 is locked in the groove and prevented from escapement until such time as the spring member is forcibly released through movement of portion 53 toward the seat.

The invention has been set forth in considerable detail in the foregoing specification but it is to be understood that the parallelogram type of folding chair is old and well known in the art and that the V-type brace is similarly old and well known in the art, and that the invention relates more particularly to the lock and release arrangement for the brace structure, and such detailed description is to be considered as illustrative and not restrictive in character.

The invention claimed is:—

1. In a folding support having two spaced ends and an intermediate structure having opposite sides hingedly connected thereto, the combination with a one piece, V-like brace means pivotally supported at its ends upon one end and extending upwardly toward the opposite end and its midportion having operative connection with the intermediate structure near the said opposite end, and an elongated member providing a socket secured to the intermediate structure, in which socket the midportion of the V-like brace means is permanently retained, the socket having a communicating depending groove positioned closest

to the said opposite end, of a one-hand releasable brace locking device having at one end a manually engageable portion available immediately adjacent said opposite end spaced from the adjacent side of the intermediate structure, an intermediate kinked portion, locking the midportion of the brace in the groove, and its other end operatively connected to the intermediate structure, simultaneous gripping and movement of said structure and the device securing initial brace means release from the locking device and brace means movement from the groove and subsequent folding of the support.

2. A structure as defined by claim 1, characterized by the one hand release locking device including a unitary spring having an anchoring portion at one end, an elongated cam portion inclined thereto, a U-shaped, V-brace seating, portion connected thereto, and an opposite end projecting therefrom oppositely from the cam portion and adapted for manual engagement and positioned immediately adjacent the adjacent edge of the intermediate structure.

3. In combination, a support, an elongated member having two ends anchored thereto, a portion therebetween offset from the support and forming a V-brace retainer portion, and a portion adjacent one end forming a brace seating groove, and an elongated spring having one end portion operatively anchored in the plane of the ends of the member, near the end thereof opposite the groove, another portion extending from the anchored end portion diagonally toward the groove, a U-shaped portion extending from the diagonal portion and forming a brace receiving seat and in registration with the groove, and an opposite end portion projecting from the seat portion for manual engagement, the mouth of the seat portion being positioned substantially transverse to the mouth of the groove forming portion.

4. In combination, a support, an elongated member having two ends anchored thereto, a portion therebetween offset from the support and forming a V-brace retainer portion, and a portion adjacent one end forming a brace seating groove, and an elongated spring having one end portion operatively anchored in the plane of the ends of the member, near the end thereof opposite the groove, another portion extending from the anchored end portion diagonally toward the groove, a U-shaped portion extending from the diagonal portion and forming a brace receiving seat and in registration with the groove, and an opposite end portion projecting from the seat portion for manual engagement, the mouth of the seat portion being positioned substantially transverse to the mouth of the groove forming portion, the elongated member at the grooved portion and the offset portion immediately adjacent thereto including an elongated slot, and the U-shaped extension and the diagonally extending portions of the spring being movable in the slot.
